UNITED STATES PATENT OFFICE

117,245

DESIGN FOR A GLIDER

Aaron S. Goldberg, Philadelphia, Pa.

Application May 6, 1939, Serial No. 84,839

Term of patent 7 years

To all whom it may concern:

Be it known that I, Aaron S. Goldberg, a citizen of the United States and a resident of Philadelphia, county of Philadelphia, State of Pennsylvania, have invented a new, original, and ornamental Design for a Glider, of which the following is a specification, reference being had to the accompanying drawing, forming a part hereof, wherein:

Figure 1 is a perspective view of a glider showing my design; and

Figure 2 is a view showing part of the front panel of the glider.

The dominant feature of my design resides in the parts shown in solid lines.

I claim:

The ornamental design for a glider, as shown and described.

AARON S. GOLDBERG.
